UNITED STATES PATENT OFFICE.

HENRY DE SMITH, OF ROCHESTER, NEW YORK, ASSIGNOR TO M. D. KNOWLTON COMPANY, OF ROCHESTER, NEW YORK, A CORPORATION OF NEW YORK.

BOX-COVERING MACHINE.

1,084,575.

Specification of Letters Patent.

Patented Jan. 13, 1914.

Application filed April 27, 1909. Serial No. 492,495.

To all whom it may concern:

Be it known that I, HENRY DE SMITH, a citizen of the United States, and resident of Rochester, in the county of Monroe and 5 State of New York, have invented certain new and useful Improvements in Box-Covering Machines, of which the following is a specification.

This invention relates to that class of machines adapted for applying a covering strip of paper or other material to paper or straw-board boxes and the like. Machines of this class usually embody a rotary-carrier for the box-form on which the boxes to 10 be covered are placed, a "cut-off" for severing the covering strip into proper lengths for the boxes to be covered, and mechanism for actuating the box-form carrier and the cut-off. In these machines the box-form 15 carrier is usually adjustable in order to permit of adjusting the position of the box-form relative to the cut-off according to the size and form of the box being covered, and also to permit of adjusting the height and 20 general location of the box-form according to the convenience of the operator. To provide for such adjustment of the box-form carrier the driving connections between the same and the driving shaft are also adjustable, and it is to such feature of the machine, 25 that is, the adjustable driving connections between the box-form carrier and the driving shaft that my present invention more particularly relates.

30 The object of my invention is to provide a box-covering machine having a new and improved operating mechanism for the rotary box-form carrier.

In carrying the invention into effect I 35 preferably provide a pivotally and slidably supported frame or holder on which is mounted the rotary box-form carrier and a drive connection between said carrier and the driving shaft, the said drive connection 40 including a belt which is mounted on said holder in a manner to be bodily movable therewith and to be maintained thereby in operative connection with the driving shaft upon adjustment of the box-form carrier.

45 Referring now to the accompanying drawings forming part of this specification, Figure 1 is a side elevation, partly broken away, of the front end of a box-covering machine embodying my invention. Fig. 2 is a par-

tial front end elevation of the same. Fig. 55 3 is an enlarged sectional detail, taken on the line 3—3 of Fig. 1. Fig. 4 is an enlarged sectional detail, taken on the line 4—4 of Fig. 1.

Like reference characters indicate like 60 parts in the different figures of the drawings.

A indicates a portion of the main frame of a box-covering machine, and B a secondary frame removably secured to said main 65 frame and having suitably mounted thereon the other main elements of the machine, including the cut-off, indicated generally by C, the box-form carrier, indicated generally by D, the holder for the box-form carrier, 70 indicated generally by E, and other associated and co-operating parts to be referred to. The association of the cut-off and box-form carrier and their supporting and operating elements in the form of an attachment 75 for removable connection with the main frame of the machine, as herein disclosed, is made the subject-matter of Patent No. 1,037,154, of August 27, 1912.

The holder E for the box-form carrier is 80 shown in the present case as being in the form of a skeleton frame composed of two parallel rods 2, 2, connected at their opposite ends by cross-heads 3, 3. The holder as thus formed is slidably mounted on a support 4 by means of its rods 2, 2, extending through openings or seats in two pairs of bosses 5—5—5—5, on said support, and the 85 said support in turn is pivotally mounted on a boss or stud 6 on the frame B, as clearly 90 shown in Fig. 3. In this manner the holder E is rendered capable of the desired slidable and pivotal adjustments for the purpose of 95 adjusting the position of the supported box-form carrier relative to the cut-off and otherwise, as indicated by the full and dotted line 100 positions shown in Fig. 1. The said adjustable holder may be secured in stationary adjusted position by any suitable means, it being preferable to provide a means that is operative at one operation to effect the securing or locking of the holder with respect to both its pivotal and sliding adjustments.

The means provided in the present case for 105 such purpose comprises a bolt 8 mounted on the pivotal support 4 with one end extending through a segmental or arc-shaped slot 9 in the frame B and having a head or nut

10 for engagement with said frame, and its other end carrying a retaining member 11 for clamping engagement with the rods 2, 2, of the holder E, and a locking member in the form of a lever-nut 12. Upon the loosening or tightening of this member 12, it will be understood that the holder and its support will be either free for adjustment or locked in adjusted position.

10 The box-form carrier, which is of usual construction, is operatively connected with a shaft 14 journaled in the front end of the holder E, which said shaft is in turn operatively connected with a driving shaft 15 through the medium of a drive connection, here shown as a chain-and-sprocket connection, the chain being indicated at 16, and the two sprockets, secured to the said shafts, being indicated at 17 and 18. The axis of the said driving shaft 15 and that of the holder E in its movement about its pivot, are coincident, and for such reason any adjustment of the holder about its said pivot does not disturb the relation between the said carrier-shaft 15 as to their distance apart, but any sliding adjustment of the holder does disturb such relation between the shafts and for such reason it is desirable that some provision be made to maintain proper operative relation of the drive belt or chain 16 with said shafts and their sprockets upon such adjustment of the holder. This is accomplished in the present case by supporting the chain 16 on the holder E in a manner whereby it will be bodily movable therewith and at the same time maintained in constant operative relation with the driving sprocket 18, such support of the chain being effected by mounting a sprocket 19 on said holder at its inner end for engaging the loop end of said chain opposite that engaged by the sprocket 17 on the carrier-shaft and so supporting the chain independent of support by the driving sprocket. As a means to take up slack in the chain and assure its positive engagement with the said driving sprocket, two idler sprockets 20, 20, are preferably mounted on the support 4 in position for engagement with the chain at opposite sides of the driving sprocket as shown.

The driving shaft 15 may be operated in any suitable manner, the same in the present case being shown as having connection through gearing 21 with a shaft 22, which latter is adapted to be driven from a driving pulley 23 through a clutch connection 24 controlled from a foot lever 25 through suitable connections, such as indicated at 26, 27 and 28.

What I claim is:

1. In a box-covering machine, the combination with a driving shaft, of a rotary box-form carrier, means supporting said carrier in adjustable position relative to said

shaft, said means being adjustable either pivotally or longitudinally, a drive belt connection between said shaft and carrier, and means adjustably supporting said belt in operative connection with said shaft.

2. In a box-covering machine, the combination with a driving shaft, of a rotary box-form carrier, means supporting said carrier in adjustable position relative to said shaft, said means being adjustable either pivotally or longitudinally, a drive belt connection between said shaft and carrier, and means movable with the carrier-supporting means adjustably supporting said belt in operative connection with said shaft.

3. In a box-covering machine, the combination with a driving shaft, of a rotary box-form carrier, a holder supporting said carrier in adjustable position relative to said shaft, said holder being adjustable either pivotally or longitudinally, and a drive belt connection between said shaft and carrier supported by said holder to be bodily movable therewith.

4. In a box-covering machine, the combination with a driving shaft, of a rotary box-form carrier, a holder supporting said carrier in adjustable position relative to said shaft, said holder being adjustable either pivotally or longitudinally, and a chain-and-sprocket drive connection between said shaft and carrier supported by said holder to be bodily movable therewith.

5. In a box-covering machine, the combination with a driving shaft, of a rotary box-form carrier, an adjustable pivotally and slidably mounted holder for said carrier, and a drive belt connection between said shaft and carrier supported by said adjustable holder to be bodily movable therewith.

6. In a box-covering machine, the combination with a driving shaft, of a rotary box-form carrier, an adjustable pivotally and slidably mounted holder for said carrier, and a chain-and-sprocket drive connection between said shaft and carrier supported by said adjustable holder to be bodily movable therewith.

7. In a box-covering machine, the combination with a driving shaft, of a rotary box-form carrier, adjustable supporting means for said carrier comprising a pivoted support and a holder for the carrier slidably mounted on the said support, and a drive belt connection between the driving shaft and the carrier supported by said holder to be bodily movable therewith.

8. In a box-covering machine, the combination with a driving shaft, of a rotary box-form carrier, adjustable supporting means for said carrier comprising a pivoted support and a holder for the carrier slidably mounted on the said support, and a chain-and-sprocket drive connection be-

tween the driving shaft and the carrier supported by said holder to be bodily movable therewith.

9. A box-covering machine, comprising a frame, a box support, an arm carrying said support, means secured to said frame and engaging with said arm intermediate the ends of the latter for supporting said arm and permitting of its longitudinal adjustment, sprocket wheels at each end of said arm, one of said sprocket wheels being connected to said box support, a chain extending over said sprocket wheels, and means for driving said chain irrespective of the longitudinal adjustment of the arm.

10. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

11. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

12. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

13. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

14. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

15. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

16. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

17. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

18. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

19. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.

20. A box-covering machine, comprising a frame, a box support, an arm carrying said support, means secured to said frame and engaging with said arm intermediate the ends of the latter for supporting said arm, sprocket wheels at each end of said arm, one of said sprocket wheels being connected to said box support, a chain extending over said sprocket wheels, and means for driving said chain.
